United States Patent Office

Des. 198,226
Patented May 19, 1964

198,226

SOCK

Paul E. Johnson, Jr., P.O. Box 324, Marietta, Ga.

Filed Dec. 16, 1963, Ser. No. 77,797

Term of patent 14 years

(Cl. D47—7)

The single figure illustrates one side of a sock embodying my design with the other side of the sock being identical in appearance.

I claim:

The ornamental design for a sock, as shown and described.
